ERNST HÜRLIMANN, OF ZUCHWIL, SWITZERLAND, ASSIGNOR TO THE FIRM
"SCINTILLA," OF SOLOTHURN, SWITZERLAND.

MAGNETO-ELECTRIC IGNITION-MACHINE.

1,360,640.

Specification of Letters Patent. Patented Nov. 30, 1920.

Application filed October 23, 1919. Serial No. 332,759.

To all whom it may concern:

Be it known that I, ERNST HÜRLIMANN, a citizen of the Swiss Republic, residing in Zuchwil, Kanton Solothurn, Switzerland, 5 have invented certain new and useful Improvements in and Relating to Magneto-Electric Ignition-Machines, of which the following is a specification.

This invention relates to magneto-electric ignition machines, more particularly for explosion motors of the kind in which the laminated iron core carrying the coil of the ignition circuit is stationary and surrounds the rotating magnetic poles by means of 15 pole-pieces. The parts which hold together the whole of the device mechanically, consequently, more especially the casing of the apparatus, must be made of non-magnetic material.

20 The object of the invention is to provide a very simple and convenient form of mounting of the laminated iron pole-pieces of the core carrying the coil in the casing in such a manner that the pole-shoes shall be retained exactly in the correct position without their being capable of being moved. According to the invention the pole-pieces the 25 relative position of which is correctly determined by means of intermediate pieces of 30 non-magnetic material, are cast into the casing, while the closing part of the yoke which carries the generating coil is detachably connected with the pole-pieces in a known manner.

35 The invention is illustrated by way of example in the accompanying drawing which shows one form of construction, and in which:—

Figure 1 is a vertical longitudinal section 40 on the line 1—1 of Fig. 2,

Fig. 2 is a vertical transverse section on the line 2—2 of Fig. 1,

Fig. 3 is a side elevation of the inner casting element or sleeve to which the pole-pieces are secured,

Fig. 4 is an end elevation of Fig. 3, and,

Fig. 5 is a fragmentary perspective view of the preferred embodiment of the invention.

50 In Figs. 1 and 2, *a* is the casing which may for instance consist of cast aluminium and into which is cast a body which is separately shown in Figs. 3 and 4, the perspective view of the whole casing being shown in Fig. 5.

55 The invention consists in the provision of

a sleeve portion *d* with laterally extending flanges, as in Figs. 3 and 4, to which are secured, by means of bolts, rivets or screws *c*, pole-pieces *b*, the latter being made of a plurality of laminations of suitable magnetic metal. The bolts, rivets or screws *c* are provided with button-like heads adapted to be engaged, or partially so, in complementary circular recesses formed in the outer wall of the flanges of the sleeve portion *d*. The 60 bolts, rivets or screws *c* may be passed directly through aligned openings of the several laminations of the pole pieces *b*, or through a sleeve of tubular metal passed through the aligned openings aforesaid, as shown in Fig. 70 2, in a manner to associate the laminæ of the pole-pieces as intimately as possible one with the other.

After the pole-pieces *b* have been so assembled and secured in position on the 75 sleeve *d*, an outer casing *a*, of aluminium or other non-magnetic material, is cast around the same, so as to form an integral structure for all practical purposes in the use of the invention, the pole-pieces being firmly held 80 in accurate adjustment and alinement against all possible displacement or removal. The upper edges of the side walls of the casing *a* being suitably reinforced, or connected by means of integrally formed 85 cross-pieces or bars *e* which are closely associated with the pole-pieces so as to further retain the latter against displacement in all directions.

As shown in the drawings, the bottom 90 wall of the outer casing *a* is formed to provide a thickened portion extending in a longitudinal direction medially of the opposite side walls thereof, whereby to provide recesses at the opposite sides of the 95 thickened portion for snugly receiving and embedding therein the lower ends of the pole-pieces *b*, which, in addition to the integrally formed cross-pieces *e*, act to more rigidly hold the pole-pieces *b* in accurate 100 position, and, consequently, the sleeve or core *d*, being securely bolted to the pole-pieces and partly incased in the outer casing, is also rigidly retained, both in a manner approximating an almost integral structure with the latter. The thickened portion of the bottom wall of the outer casing *a* is formed with its upper face transversely concaved, the curvature of which is laid on the arc of the circle described by the arms 110

ture bore of the machine. The opposed faces of the pole-pieces *b* are similarly formed and curved, and the armature bore therebetween is disposed concentrically in 5 alinement with the circular bore of the sleeve portion or core *d*.

It is to be understood that other suitable means may be employed, or resorted to, for securing the pole-pieces in proper position, 10 in lieu of the sleeve *d* and the fastening devices as shown, without departing from the spirit and scope of the invention.

What I claim is:—

In a magneto-electric machine, a cylindrical core, laterally extending flanges formed at one end of said core, pole-pieces bolted to said flanges in vertically spaced relation, said pole-pieces having opposed faces approximating arcs of the circle described by the armature bore of the machine and disposed concentrically of and in alinement with the bore of said core, an

outer casing of a non-magnetic material cast around said core and the pole-pieces carried thereby, an intermediate portion of the bottom wall of said outer casing being of a greater thickness than the opposite outer portions thereof whereby the lower ends of the pole-pieces are firmly embedded in accurate alinement and position, the upper 30 face of the thickened portion of the bottom wall of said outer casing being transversely curved correspondingly with the curvature of the opposed faces of said pole-pieces, and cross-bars connecting the opposite side walls 35 of said outer casing and contacting the opposite outer sides of an intermediate portion of the upper ends of said pole-pieces whereby the latter are more firmly retained in position.

In testimony whereof I have signed my name to this specification.

ERNST HÜRLIMANN.
